Letters Patent

The Subject referred to in these Letters Patent, and making part of the same, is a stamping or description in the words of the said James C. Hampton himself of his improvement in the Power Loom.

It all doth now witness, Be it known that I James C. Hampton of Marnayunk, in the County of Philadelphia and State of Pennsylvania have invented an improvement in the power Loom which improvement is intended to be applied to the weaving of Checks and Crop Bars, and I do hereby declare that the following is a full and exact description thereof.

In the ordinary mode of weaving Checks and Crop Bars by power looms, the width of a stripe of any particular Color is governed by the number of throws of the shuttle, and should the web some but or break previous to completing the stripe the shuttle still continues in motion until having performed the requisite number of throws "the boy changes, and the bing into another shuttle containing a different Color and thereby produces an irregular stripe. By my improvement the change of bays is independent of the number of throws of the shuttle being governed by the width of stripe actually woven which I speak in the following manner. as fig 1 represents the cloth passing over the pattern wheel B. C. C. is a pattern wheel in end of cloth beam and running with it R. D. D. are small cones set at requisite distances on either side of wheel B. C. by the revolving of pattern wheel, these small cones act on the projecting pins C. C. fig 2, which gives the rod D a slight reciprocating motion, is a short arm projecting from the stand E. H. and attached by a movable joint to rod B. H. are located running vertically in their following E. H. and horizontally on their fulcrum F. H. is an arm projecting from revolving shaft R. R. the reciprocating motion of H. brings the lever H. H. in the opposite under the arm H. by which they receive a vertical movement the depression of the beam attached to lever P. fig 3. goes up the rod H. and with it goes R. R. the depression of one connected with the beam H. acts on the knee of lever P and by withdrawing a catch from rod C.

P. D.

allows the beam to fall. The rotation of Clothi-beam is effected in the usual man-
ner by means of ratchet and wheel which causes it to revolve only as the top of
beam is raised in of course should the ratchet break or run out, the beam and with it the
gallows wheel remains quiet and thus the box remains unchanged however
frequent the shuttle may be thrown.

What I claim as my invention is the mech-
anical device of changing the beam independent of the number of throw-
es of shuttle by means of the stripe actually worn and thus I claim whether the
beam is effected precisely in the manner set forth or in any other manner
on the same principle and producing the same effect.
